UNITED STATES PATENT OFFICE.

LUIS GONZALEZ DÁVALOS, OF CHICAGO, ILLINOIS.

DESIGN FOR A BRIDGE FOR STREET-CROSSINGS.

SPECIFICATION forming part of Design No. 22,826, dated October 3, 1893.

Application filed February 18, 1893. Serial No. 462,922. Term of patent 7 years.

To all whom it may concern:

Be it known that I, LUIS GONZALEZ DÁVALOS, a citizen of the Republic of Mexico, residing at Chicago, in the county of Cook and State of Illinois, have invented a certain new and useful Design for a Street-Crossing Bridge; and I do hereby declare the following to be a full, clear, and exact description of the invention, such as will enable others skilled in the art to which it appertains to make and use the same.

My invention relates to a design for an ornamental removable bridge for streets or boulevards in cities.

The invention consists in the shape or configuration of the bridge as a whole. This shape consists, first, of upwardly extending inclined lower sections F, rising from the ground; second, of horizontal sections D, connecting with the upper ends of sections F;

third, upwardly inclined segmental sections A, or springers, rising from the piers, C, and connected at their lower ends to the horizontal sections D; fourth, the segment H, of an ovoidal arch, the lower ends of the arch connected with the upper ends of the sections A, and fifth, the piers C, of oblong shape connected with the bottom of the landing D, and with the lower ends of the sections A, and the upper ends of sections F.

Having thus described my invention, what I claim is—

The design for a street crossing bridge of the shape herein shown and described.

In testimony whereof I affix my signature in presence of two witnesses.

L. GONZALEZ DÁVALOS.
